[57] CLAIM

The ornamental design for a throwing game projectile,
as shown and described.

DESCRIPTION

FIG. 1 is an isometric view of my new design of a
throwing game projectile;

FIG. 2 is a top view of the throwing game projectile
shown in FIG. 1;

FIG. 3 is a side elevational view of the throwing game
projectile shown in FIG. 1;

FIG. 4 is a front elevational view of the throwing game
projectile shown in FIG. 1; and

FIG. 5 is a rear elevational view of the throwing game
projectile shown in FIG. 1.

FIG. 1.FIG. 2.FIG. 3.FIG. 4.FIG. 5.
